UNITED STATES PATENT OFFICE.

WILLIAM O. BODE AND LAWRENCE J. HAMING, OF LOUISVILLE, KENTUCKY.

THEFTPROOF LAMP GLOBE.

Application filed June 24, 1924, Serial No. 722,178. Renewed June 9, 1928.

This invention relates to improvements in theft proof lamp globes, especially those adapted for the ordinary electric light sockets or the like, and has for one of its principal objects the provision of a lamp globe which when placed in the socket will be impossible to remove without destroying the operating efficiency of the globe itself.

One of the important objects of this invention is the provision of a theft proof lamp globe which shall be so constructed that unauthorized removal is rendered practically impossible without leaving the bulb unfit for subsequent use, but which at the same time will not damage the bulb to an irreparable degree.

A further important object of this invention is the provision of a theft proof lamp globe for electric light sockets, signs, or the like, which will be so constructed that any unauthorized removal of the same will act to automatically destroy the vacuum existing inside the bulb, but which will destroy the same in such a manner that the vacuum may be restored by means of suitable equipment.

Other and further important objects of the invention will be apparent from the disclosures in the accompanying drawings and following specification.

The invention, in a preferred form, is illustrated in the drawings and hereinafter more fully described.

In the drawings:

Figure 1 is a vertical elevation of the improved theft proof lamp globe of this invention shown as affixed in a socket, parts being broken away.

Figure 2 is a sectional view, taken on the line 2—2 of Figure 1, looking in the direction indicated by the arrows.

Figure 3 is a detail view illustrating the locking means as applied to the ordinary lamp socket now in use.

As shown in the drawings:

The reference numeral 10 indicates generally the outer casing of an ordinary lamp globe socket or the like having an operating key or switch 12. It will be obvious that the invention may be applied to any electric light globe socket, whether fixed or portable.

Mounted in the usual manner in the casing 10 is the ordinary socket supporting insulating element 14 having the usual metal screw threaded socket 16 affixed thereto and with the usual electrical connections applied to

the same. A notch or slot 18, as best illustrated in Figure 3, is cut into the screw threaded socket 16 preferably along the lines of one of the screw threads, and adapted to co-operate with this notch is a locking element in the form of a leaf spring 20 suitably affixed to the screw threaded socket 16 by means of rivets 22 or the like and having its forward free end projecting inwardly into the opening 18 as best illustrated in the sectional view in Figure 2.

The theft proof lamp globe of this invention is best illustrated in Figure 1 and comprises the ordinary globe as illustrated at 24 having the usual base 26 composed of a metallic screw threaded contact member adapted to co-operate with the interior face of the screw threaded socket 16. A circular opening is provided in the side of the screw threaded base member 26 and through this opening projects a nipple or the like 28 which forms an integral part of the material of the glass globe 24 and which, if broken off or opened, will act to admit air to the interior of said globe. If the lamp is removed while burning the filament will be completely burned up and it will not be feasible to repair the globe.

The operation is as follows:

Upon the globe 24 with the screw threaded base 26 being inserted into the socket 16, rotation of the same to screw the globe into lighting position will cause the nipple 28 to ride in the space between the walls of the lamp base and the socket and eventually under the inwardly projecting end of the locking leaf spring member 20. When the globe shall have been adjusted into lighting position the nipple 28 will have assumed a position immediately beyond the inwardly projecting end of the locking member 20, as best illustrated in the sectional view in Figure 2.

Upon any attempt to unscrew the globe or remove the same from its socket the action of the extending glass nipple 28 against the end of the locking member 20 will act to prevent such retrograde movement and, if sufficient force is applied, the glass nipple 28 will be broken off, thereby allowing an influx of air into the interior of the globe 24 with the result that the vacuum is destroyed and the lamp is unfit for further use without extensive repairs.

In the lamp locking devices heretofore on the market the globe has been practically

destroyed by its unauthorized removal from the socket and repairs are rendered very difficult, if not impossible. By the improved device of this invention the globe is only 5 temporarily rendered unfit for further service, but by the use of proper equipment can be again reclaimed for use. This equipment, of course, is unobtainable so far as the ordinary light globe thief is concerned.

10 We are aware that many changes may be made and numerous details of construction varied throughout a wide range without departing from the principles of this invention, and we therefore do not purpose limiting the patent granted hereon otherwise than 15 as necessitated by the prior art.

We claim as our invention:

1. A theft proof lamp globe, including in combination an exhausted glass globe, a 20 metallic base thereon, and means in the base for allowing of the projection of a portion of the globe therethrough, said projection being adapted to act to destroy the vacuum in the globe upon tampering therewith.
- 25 2. A theft proof lamp globe and socket, including in combination an exhausted globe, a metallic contact base on the globe, a

portion of the globe extending through an opening in the metallic contact base, a receiving socket for the globe, and means on the socket adapted to lock against and break off said projecting portion upon removal of the globe from said socket.

3. A theft proof lamp globe and socket, including in combination an exhausted globe, a metallic contact base on the globe, a portion of the globe extending through an opening in the metallic contact base, a receiving socket for the globe, and means on the socket adapted to break off said projecting portion upon removal of the globe from said socket, said means comprising a one-way latching member in the form of a leaf spring attached to the outer face of said lamp socket, one end of said leaf spring projecting inwardly through a slotted opening in the socket and adapted to co-operate in locking relation with the projection on the lamp globe base.

In testimony whereof we affix our signatures.

WILLIAM O. BODE.
LAWRENCE J. HAMING.
